2 SHEETS-SHEET 2.

UNITED STATES PATENT OFFICE.

EVA O. FARNSWORTH, OF MINNEAPOLIS, MINNESOTA.

COMBINATION-UNDERGARMENT.

1,121,005.

Specification of Letters Patent.

Patented Dec. 15, 1914.

Application filed December 27, 1909. Serial No. 534,915.

To all whom it may concern:

Be it known that I, EVA O. FARNSWORTH, a citizen of the United States, residing at Minneapolis, in the county of Hennepin and State of Minnesota, have invented certain new and useful Improvements in Combination-Undergarments; and I do hereby declare the following to be a full, clear, and exact description of the invention, such as will enable others skilled in the art to which it appertains to make and use the same.

My invention has for its object to provide an improved combination undergarment for women, and, to this end, it consists of the novel devices and combinations of devices hereinafter described and defined in the claims. As preferably constructed, this improved undergarment combines in one piece four garments usually worn at the same time, to-wit, drawers, skirt, bust supporter or corset and skirt supporter.

The improved undergarment is illustrated in the accompanying drawings, wherein like characters indicate like parts throughout the several views.

Referring to the drawings, Figures 1 and 2 are, respectively, front and rear elevations of the combination garment; Fig. 3 is a horizontal section taken on the line x^3-x^3 of Fig. 1; Fig. 4 is a sectional perspective view of the garment, some parts thereof being broken away; Fig. 5 is a fragmentary perspective looking at the inner surface of the front of the garment; and Figs. 6 to 10, inclusive, are plan views showing the component parts of the garment.

The drawer legs are independently constructed, each from a piece of cloth 1 (see particularly Figs. 4 and 8) stitched together at their ends by short vertical seams 2 located at the inner sides and lower portions of the drawer legs. Fig. 8 shows one drawer leg laid out flat.

The skirt piece 3 (shown in detail in Fig. 9) is made with an upward taper, and at its upwardly converging edges is stitched to the backs of the two drawer legs, by vertical seams 4. The upper edges 5 of the leg pieces 1 and the upper edge 6 of the skirt piece 3 are stitched to the lower edge of a girdle 7, which, at the front opening of the garment, is provided with coöperating buttons and button-holes, or other suitable fastenings 8. This girdle serves the purpose of a corset and is preferably made from

two thicknesses of bias-cut cloth, each ply being a single piece. Also, as shown, the girdle is reinforced by vertical strips of cloth or binding fabric sewed thereto at suitable intervals. The front portion of the girdle is also preferably provided with vertical sheaths 9 in which whalebones 10 are adapted to be inserted. A little more than one-half of the piece from which the girdle 7 is made is shown as laid out flat in Fig. 7.

The upper portion of the garment, to-wit, bust supporter and shoulder straps, is made from a single piece of cloth, a little more than one-half of which is shown in Fig. 6. The body portion 11 thereof, which constitutes the bust supporter, is stitched to the upper edge of the girdle 7, and at its front ends, it is provided with coöperating buttons and button holes, or other suitable fastenings, alined with the fastenings in the front of the girdle. The shoulder straps 12 are, as above indicated, preferably made as parts of the body or bust supporter 11.

A skirt supporter, in the form of a band 13, shown in detail in Fig. 10, is stitched to the waist line of the girdle 8 and is provided with buttons 14 to which a dress skirt or underskirt may be attached.

The girdle 7, as previously indicated, is not stiffened at the back or sides but only at the front portion, and the whalebones 10, which are grouped at opposite sides of the front closure of the girdle and preferably extend slightly beyond the lower edge of the bust supporter, as shown in Fig. 5, are so placed as to support the bust comfortably yet effectively from below. As thus made, the girdle, if of the proper size, does not constrict or bind the body, and nevertheless the bust is held up properly if the required number and spacing of the front stiffening members is employed.

The undergarment above described combines in a single garment, drawers, skirt, bust supporter and skirt supporter. It comfortably and perfectly sustains the heaviest bust from the shoulders, relieving the individual of the discomfort of its weight. The effectiveness of the bust supporter is increased by the unique device for the insertion of whale-bones, the number of which will depend upon the weight of the bust. It is a perfect substitute for the corset in that particular, and an improvement in other respects, as it permits natural circulation, perfect respiration and freedom for every mus-

cle. All this is accomplished without resorting to a system of bands or strings which necessitate countless buttons and button-holes, making the garment impracticable 5 for easy laundrying.

The skirt supporter in no way mars the appearance of the combination, as it acts as a cover for joining the upper and lower parts without creating bulk or attracting 10 special notice as it follows the curve of the body.

The garment is particularly adapted to warm weather, as it can be worn without chemise or knitted vest. Its construction 15 without bands gives no opportunity for girding the soft parts of the body, while it follows the natural curves, preserving the contour of the figure and elegance of movement. It is so constructed that the form can 20 be improved in an exceedingly satisfactory way by a nice provision for the insertion of extra fullness. The whalebones, which keep the front smooth, can be easily removed for the laundry and as easily inserted.

25 The defects of many other combination garments, to-wit, insufficient bust support, clumsy methods of supporting skirts with restricting bands and unsightly buttons, which make the garment difficult to launder, 30 are overcome by the careful selection and handling of the materials suited to the different parts, making the garment graceful, durable, hygienic, and conventional according to the latest modes.

35 What I claim is:
1. A combination undergarment compris-

ing a girdle having a front closure and consisting of soft material cut on the bias to fit the form, a bust-supporter applied to the top of said girdle, and upright stiffeners 40 associated with the front sections only of the girdle at opposite sides of the closure and extending substantially from top to bottom of the girdle; substantially as described.

2. A combination garment, comprising a 45 girdle having a front closure and consisting of soft material cut on the bias to fit the form, a bust-supporter applied to the top of said girdle, upright stiffeners associated with the front section only of the girdle at 50 opposite sides of the closure, and upright reinforcing strips of soft material for the intermediate unstiffened portions of the girdle; substantially as described.

3. A combination garment made up of a 55 girdle having a front closure and consisting of soft material cut on the bias to fit the form and provided with upright reinforcing strips also of soft material, a bust-supporter applied to the top of said girdle, upright stiffeners associated with the front sections only of the girdle at opposite sides of the closure, and a lower or skirt portion attached to the lower edge of the girdle; 60 substantially as described.

In testimony whereof I affix my signature in presence of two witnesses.

EVA O. FARNSWORTH.
